Inventor:
NELSON S. WELK.

By *Dodson & Roe* *Atty.*

UNITED STATES PATENT OFFICE.

NELSON S. WELK, OF ATHENS, OHIO, ASSIGNOR TO THE McBEE BINDER COMPANY, OF ATHENS, OHIO.

BINDER FOR LOOSE-LEAF FILES.

Application filed March 29, 1923. Serial No. 628,425.

My invention relates to the art of book binding, and particularly as applied to loose leaf filing devices, and has for its object to provide new and novel means for not only 5 quickly and easily accomplishing the purpose of inserting or withdrawing leaves from the file, but also to provide a construction that will add stability to the binding posts, and tend to strengthen, rather than 10 weaken, the same.

My invention consists of certain details of construction hereinafter set forth, pointed out in my claims and illustrated in the accompanying drawings in which Fig. 1 15 shows a top view of a loose leaf binder fitted out with my device;

Fig. 2 shows a plan view of my device, the top plate being removed to disclose the construction and method of operation of the 20 parts;

Fig. 3 shows a sectional view taken on the line 3—3 in Fig. 2; and

Fig. 4 shows a sectional view taken on the line 4—4 in Fig. 2.

Referring to the accompanying drawings the reference numeral 10 is used to indicate the lower cover of a loose leaf file to which 25 are secured a plurality of upwardly projecting posts 11, to receive the perforated file sheets 12. To the upper cover 13 I have secured a flat tubular member or clamping bar 14, slotted at 15 to register with the posts, said slots projecting inwardly from the outer edge surface of the member. A

30 35 slidably mounted plate 16, provided with recesses 17 to register with, but much wider than, the slots 15, is secured in proper relationship within the member 14, the construction being such that when the plate is

40 positioned at one end of its limit of movement the post receiving slots will be perfectly clear and free to receive the posts. Inclined flat lock springs 18 are secured to the sliding plate and so mounted that when the

45 50 member 14 has been placed on the posts which are fitted within their respective slots, and the plate moved laterally (in its slideable movement operation) the springs will contact and abut against their respective posts, the tension of the spring providing pressure for them to firmly grasp the posts.

Also these springs are inclined (as shown in Fig. 3) and so mounted as to engage the opposite side of the posts from the side engaging the member 14 at the inner ends of 55 the slots in such a manner that the spring contacting the post is forced into a further inclination, thus increasing the tension of the spring in its engagement against the post, and this arrangement, obviously, forms 60 a sure and satisfactory locking device. Means 19 consisting of a shaft secured to the plate 16 projecting through a longitudinal slot in the plate 14 and provided with enlarged operating head or button for causing 65 the sliding movement of the plate are provided, as shown.

In the drawings I have illustrated the preferable construction I use, but it is obvious this may be changed and altered in 70 its details without affecting my invention and I do not desire to be understood as limiting my invention except as set forth in the appended claims.

Having thus described my invention what 75 I claim and desire to secure by Letters Patent of the United States, is:

1. A binder for loose leaf files comprising a lower cover with binding posts secured thereto, a slotted member to be fitted over 80 said binding posts, a sliding member secured to the slotted member and springs thereon inclining upwardly from the horizontal to engage the posts and lock them to the slotted member, when the sliding member is 85 moved in one direction.

2. A binder for loose leaf files comprising a lower cover and binding posts extending upwardly therefrom; an upper cover; a slotted member, to fit over the binding posts, 90 secured to the upper cover; a plate slidably secured to the slotted member; flat springs, their inner longitudinal edges being elevated, positioned on said plate in such manner that when the plate is moved to one position 95 they will not extend into, or across, the slots but when the plate is moved to its other position the springs will be thrust across their respective slots and engage the posts so as to firmly lock them to the slotted member.

NELSON S. WELK.
